PC(57) **CLAIM**

The ornamental design for an operation panel for elevator, as shown and described.

DESCRIPTION

FIG. 1. is a perspective view of the front, right, and top sides of an operation panel for elevator as viewed from a front showing my new design;

FIG. 2. is a front view thereof;

FIG. 3. is a rear view thereof;

FIG. 4. is a right side view thereof; a left side view being a mirror image thereof;

FIG. 5. is a top plan view thereof;

FIG. 6. is a bottom plan view thereof; and,

FIG. 7. is a reference enlarged end view of cutting part at 7-7 in FIG. 2 omitting the internal mechanism.

1 Claim, 7 Drawing Sheets(56)
